UNITED STATES PATENT OFFICE.

GEORGE P. SCHMITT, OF OAKLAND, CALIFORNIA.

GAS RADIATOR.

Application filed January 14, 1926. Serial No. 81,238.

My invention relates to radiators, and it has special reference to radiators in which heat is generated by means of a gaseous fuel, and the heated gases are caused to circulate through the radiators for heating the surrounding air by direct radiation.

In such radiators of this class as are provided with spaced radiating loops therein, it has hitherto not been found possible to arrange the heating elements thereof so that the flames from the burning gases and their polychromatic effects upon and about the said elements are visible to observers in a room, such as the fire and glow exhibits of the common open fireplace.

The principal object of my invention is to provide a radiator of this class with heating elements and to arrange a transparent plate or facing in front of the elements so that, a person in the vicinity of the radiator may watch the pleasing effects of the burning gases in combination with the incandescent heating elements, while at the same time he is enjoying the warmth from the radiator.

Another object of the invention is to arrange a transparent plate in front of the heating elements in a radiator so as to prevent the clothing of a person in close proximity to the radiator from being drawn into the flame and from being set on fire thereby.

A still further object is to construct a radiator of this class with a transparent plate of glass, or the like, preferably of a heat-resisting kind, for the heating elements in the radiator in such a manner that the plate can be easily attached to or detached from the radiator, and so that the liability to the breaking of the plate is minimized.

Other objects and advantages of my invention will be understood from the following detailed description thereof in conjunction with the accompanying drawings, in which:

Figure 1 is a rear elevation of a five-loop radiator constructed in accordance to my invention;

Fig. 2 is an end elevation thereof;

Fig. 3 is a vertical section taken along the line 3—3 of Fig. 2 and looking toward the transparent plate, the heating elements being removed.

Fig. 4 is an enlarged central sectional view through one of the radiating loops;

Fig. 5 is a similar sectional view of the middle loop at its top;

Fig. 6 is an enlarged front elevation of one of the heating elements;

Fig. 7 is a side elevation of Fig. 6 with a portion of the element broken away; and

Fig. 8 is a horizontal section taken through the heating element.

Referring to the drawings, I show therein a radiator R, which comprises five loops, though a greater or lesser number of loops may be used according to the space or size of the room to be heated. Each loop is complete in itself and has no circulatory connection with the other loops except at the top of the unit assembled radiator. The separate loops are joined together by rods at the top and the bottom, as shown at 1 and 2.

At the extreme top the individual loop sections open into each other and form a chamber 3, which constitutes a superheater, and also open into each other below the superheater and form a combustion chamber 4, which is separated from the superheater by an angular wall 5. Otherwise, the individual loop sections are separate or insulated from each other and are preferably sealed at their joints by cement in the usual manner.

Near the top of each loop section is a combustion passageway 6. These open toward each other so as to form a continuous passageway through the radiator, and at the ends of which the passageway is closed by walls 7 and 8 in the outer loop sections. To each of these walls is removably secured at its lower end, the upper reduced part of a fire box 9 at respective end walls 10 and 11 of the box. This reduced part fits between a baffle wall 12, which is formed in all the loop sections, and another wall 13, which is formed opposite to the baffle wall 12 and is integral with the angular wall 5 in four of the loop sections, as is shown in Fig. 4, but is in the middle loop section 14 substituted by a wall 15, corresponding in height with the height of the baffle wall 12, as is shown in Fig. 5.

The fire box is open at its top, and also at its bottom for the inlet of air and is in its end walls and near its bottom provided with openings for mounting therein a burner tube 16, which is provided with burner tips 17. Over each burner tip the tube is adapted to hold a heat-radiating element 18 of lava

composition or other equivalent material having incandescent properties. At the bottom of the fire box the back thereof has its edge turned inward, Fig. 4, so as to form a longitudinal flange 19 adapted to receive thereon a protecting element 20 which may be cemented to the back, and which may be of a fire brick formation or some other heat-resisting body. The fire box is at its bottom front also provided with an inward and upward turned edge, so that thereby a longitudinal groove 21 is formed which is adapted to receive therein the lower edge of a transparent plate 22, which preferably is of a heat-resisting glass, such as that known by the tradename of "pyrex," in order not to be liable to breakage from the heat of the burner. Under the reduced portion at its top, the fire box is longitudinally provided with a downward flange 23, which with the front of the fire box forms an upper groove 24 adapted to receive therein the upper edge of the glass plate. Both grooves 21 and 24 are of a width sufficient to allow a clearance play of the plate therein, and the height of the plate is preferably such that it allows the plate to be lifted up into the upper groove 24 and to clear the upturned edge at the lower groove 21 when it is desired either to insert the plate into or to remove it from the fire box, as is shown in Figs. 4 and 5. The front of the fire box is thus open, but normally closed by the plate, so that the flames from the burner tips and their poly-chromatic effects upon the radiating elements 18 may be visible through the glass plate. Sufficient space is provided between the bottom of the fire box and the series of loop sections for allowing the fire box to slide under the lower edges of the walls 12, 13 and 15 into place for connecting it and the burner tube with the radiator R or for disconnecting them therefrom.

As has already been mentioned, the wall 15 of the middle loop unit extends upward about to the height of the baffle wall 12. This is for the purpose of providing a direct opening to the flue 25 at the rear of the loop section. A damper 26 adapted to close this opening is mounted on a rod, which is supported by the walls of the loop section 14 and extends to the outside of the radiator, may be operated by a bundle 27 at the end of the rod for causing direct suction through the flue at the initial operation of the radia-

tor, or for preventing such suction when the radiator is hot and functioning properly.

In a former construction of a gas radiator, for which I was granted Letters Patents, No. 1,470,293, in the United States on October 9th, 1923, the gas burner was arranged in the upper part of the radiator. For the purpose of the present invention the gas burner is placed in the lower part of the radiator, as has already been described and as is clearly shown in Figs. 3 and 4. With the exception of the construction and the arrangement of the fire box with the glass plate and the firebrick therein, the burner tube, the heating elements thereon and minor details in connection with the radiator, the construction disclosed in the present invention is similar to the one shown in the aforementioned patent, and the operation of both radiators is substantially identical. The operation of the radiator disclosed in the present invention will therefore be understood from the description in the Letters Patent referred to, so that a repeated description appears superfluous.

Having thus described my invention, I claim as new and desire to secure by Letters Patent of the United States the following:

In a gas radiator comprising separable gas-circulating loops secured together so as to form longitudinally through the radiator a combustion passageway closed by end walls, said loops opening into each other at the top thereby defining a superheater chamber, a fire box provided at its top with an open reduced portion fitting in the said longitudinal passageway and with its closed ends detachably secured to said end walls, the fire box also having an open front wall and an open bottom; the front wall having at the bottom an inward and upward turned edge forming a longitudinal groove; a downward flange formed at the top of the fire box and under the reduced portion so that thereby a longitudinal groove is formed at the front of the fire box and above the first-mentioned groove; a gas burner mounted longitudinally in the fire box and near the bottom thereof; and a transparent plate slidably and removably mounted in said grooves and normally closing said front wall.

In testimony whereof, I affix my signature.

GEORGE P. SCHMITT.
